UNITED STATES PATENT OFFICE.

ROBERT M. POTTER, OF JERSEY CITY, NEW JERSEY, AND REINHOLD BOEKLEN, OF BROOKLYN, NEW YORK, ASSIGNORS OF ONE-THIRD TO ISRAEL COOK, OF BROOKLYN, NEW YORK.

APPARATUS FOR GENERATING ILLUMINATING-GAS.

SPECIFICATION forming part of Letters Patent No. 325,766, dated September 8, 1885.

Application filed June 23, 1885 (No model.)

To all whom it may concern:

Be it known that we, ROBERT M. POTTER and REINHOLD BOEKLEN, both citizens of the United States, said R. M. POTTER a resident of Jersey City, in the county of Hudson and State of New Jersey, and said R. BOEKLEN a resident of the city of Brooklyn, in the county of Kings and State of New York, have invented a new and useful Improvement in Apparatus for Generating Illuminating-Gas, of which the following is a specification.

This invention relates to a cupola gas-generating furnace and connected apparatus, and includes novel features of construction, where-
15 by the generator is made more convenient and effective in operation, and whereby the manu-
facture of fixed illuminating-gas is made prac-
tically continuous in a single furnace. Gas is
made by distilling bituminous coal, decom-
posing steam, vaporizing hydrocarbon oil, and
20 combining and fixing the resulting gases and
vapors in a heated fixing-chamber. A par-
tial vacuum is maintained in the generator by
the operation of an exhauster, and a small
25 proportion of moist air is thereby drawn into
the furnace to keep up combustion of fuel near
the grate while the coal above is being dis-
tilled, fresh coal being fed in continuously, or
as desired, through a sealed charger, and the
30 spent fuel being drawn off through a sealed
chamber.

The novel features of the apparatus constit-
uting our invention will be defined in the
claims.

35 In the accompanying drawings, Figure 1
represents a longitudinal central vertical sec-
tion of the apparatus for generating, fixing,
scrubbing, and exhausting and delivering the
gas to the purifying apparatus according to
40 our invention. Fig. 2 is a detached horizon-
tal section of the cupola, the line of section
being indicated by the letters *a b* in Fig. 1.
Fig. 3 is a detached vertical section of sev-
eral grate-bars in connection with the raking
45 device. Fig. 4 represents a sectional eleva-
tion of a modification of the apparatus.

A represents the generating-cupola; B, its
feed-hopper; C, its grate; D, its blower; E, its

distilling, decomposing, and generating cham-
ber; F, its fixing-chamber; G, its delivery-
50 pipe. W is a superheater and secondary fix-
ing-chamber; H, a scrubber, and I the gas-
exhauster, from which the gas may pass
through a condenser and then through the
purifier to the holder, or pass directly to the
55 purifier and then to the holder.

The grate C is made of a series of bars ar-
ranged on a considerable inclination, as shown,
to cause the coal to slide readily toward the
sealed outlet J, from which, when opened, the
60 coal is allowed to discharge into a sealed ref-
use-chamber, K.

L represents the ash-pit, which is furnished
in its bottom with a water-pan, L', and it has
a water-supply pipe, M, provided with a
65 proper stop-valve. With said pan is also con-
nected a steam-supply pipe, N, and an air-
supply pipe, O, both furnished with proper
stop-valves, and the steam-pipe also with a
drip-pipe and cock for drawing off, when re-
quired, the condensation of the steam. Said
pan may be also supplied over it with a seal
70 to close its communication with the ash-pit L
during the time required for removing the
ashes from said pan, for which purpose said
pan is provided with a proper seal or door, P,
75 and the ash-pit with a branch steam-pipe, N',
from the pipe N, and with a proper stop-
valve in said branch to furnish, when required,
steam in the ash-pit. Under the grate-bars
80 C' are arranged several lateral raking-shafts,
C'', upon each of which are employed several
raking-cams Q, each cam having a strong
hub held permanent upon its shaft, and from
85 its hub are one or more projecting cam-arms,
Q', which pass in the air-spaces between the
grate-bars into the coal above, so that by turn-
ing the shafts and the cams in proper direc-
tion the coal is moved forward toward the
90 outlet J.

The feed-hopper B has two bottoms, B', each
provided with a quick-opening seal-door, S,
for alternate opening during the feeding of
coal into the cupola, and to prevent undue
admission of air in the cupola. The opening
95 from the hopper into the cupola is arranged

at proper height above the grate to provide for a suitable bed of coal over the grate to remain.

The refuse-chamber K has the seal-door K', 5 to afford access into it for removing the refuse coal and ashes therein accumulating during such time, while the seal-door J' employed on the outlet J is kept closed.

Each of the seal-doors S and J' is hinged to 10 its seat, and upon a lateral shaft, T', is employed a crank, T, which is connected by a link, S', to the back of the door, as shown; and said shaft projects outside and passes through a proper stuffing-box on the side, and 15 is furnished on its outer end with a lever, U, for opening and closing and locking the door by setting the crank on its center, as shown.

In the upper portion of the chamber E is 20 or are arranged one or several lateral oil retorts, V, which are made each with a flat side built vertically in the lining of the cupola, and with a semicircular side projecting into the chamber E. The cupola is constructed for each retort with a proper opening on its side 25 for inserting or removing said retort for repairing or substituting a new one for the same. Over each of said openings is provided a suitable cap, V', to close the same air-tight.

The interior of each retort is divided into 30 an upper and lower compartment by a longitudinal horizontal loose tile partition, V'', which commences on the front end, but terminates before meeting the rear end of said interior space, thereby allowing a passage, V''', from the lower to the upper compartment, which latter has on its forward end the discharge-opening q into the cupola or its chamber E.

c represents the oil or naphtha supply pipe. It has a branch pipe for each retort V, and each branch terminates with a horizontal oil-nipple, d, passing into the front end of the retort, and is furnished with a proper stop-cock, f, to regulate the supply of oil on its vertical part. On the rear of the horizontal nipple is attached a secondary stop cock, e, for the purpose of entering a rod into the nipple and clear it from soot.

In generating the gas the oil is allowed to flow into the nipple d, which passes the oil into the lower compartment of the retort. Its vapors pass under the aforesaid partition until meeting the passage V''', and from it the vapor passes through the upper compartment and discharges from the opening q into the chamber E.

The top of the chamber E is arched, as shown, and has a large central outlet, F', upward into the fixing-chamber F, which is provided with several tile shelves, F'', arranged above one another, with spaces between and having connecting openings g, causing a zig-zag motion and alternate dividing current of the gas passing between them, whereby the gas is fixed by their incandescent or highly-heated condition.

The generating-chamber E is furnished with

several bulls'-eyes or sight-hole fixtures, X, to enable the operatives to observe the condition of the interior at all times during the operation. Said chamber may be provided with additional seal-doors for access to the grate or other parts besides those now shown.

The fixing-chamber F is also arched at its top, which is provided with a central gas-main outlet, Y, over which the vertical pipe Z is employed to connect said outlet with the gas-delivery pipe G. Said pipe Z has an open top covered by a seal-door, h, which is opened while the fire is being blown up and renewed 80 by means of the lever i and rod j from the floor. A secondary lever, k, is employed to lock and unlock said door h, which is hinged to its seat and connected by a link, l, with the lever i. The lever k has a short arm with a 85 friction-roller, m, passing over an inclined rib on the upper side of the door and pressing the same home upon its seat. The long arm of the lever has a rod suspended on it to operate the same from the floor.

All seal-doors are made with a circular groove, n, facing the door-seat and properly packed with asbestos packing for closing tightly with facility upon their seats.

The delivery-pipe G is furnished near the 95 cupola with a proper gate-valve, o, for closing its connection with the cupola any time required. In small gas-works, and with frequent blowing up of the fire, the fixing-chamber F may be kept sufficiently hot or incandescent 100 to fix the gas, and the pipe G may directly deliver the gas to the scrubber H, and from it the same may directly pass to the exhauster I; or it may pass prior to the exhauster through a proper condenser, H'. In larger works, or 105 when generating gas very rapidly, or with long periods before blowing up the fire, it is far preferable to employ a superheater, W, (shown in Fig. 4,) into which the gas-delivery pipe G conducts the gas from the cupola. Said superheater is constructed with a vertical furnace containing a vertical retort, W'. Said furnace has an ash-pit, p, a grate, r, and is properly lined with fire-brick, and at the side, near its top, is connected its flue or chimney s. A proper space for the heated products of combustion is made between its lining and the periphery of the retort, which may be made entirely of fire-clay; but it is preferred to have it made of metal and covered 110 with fire-clay, as shown, allowing a fair space between the metal and clay cover for expansion of the metal within the cover. The top of the retort joins the pipe G with a flange.

The clay part of the retort has a large shoulder on its top end, which rests upon the top of the furnace. The lower end of the retort has a throat, t, to rest in the lining of the furnace, and the horizontal metal throat within is properly united with the vertical metal retort, 120 and also with the metal side of the furnace, which has outside from said throat a pipe, u, to connect with the scrubber or a condenser, H'. Several lateral flues, v, are made in the

retort, as shown, to fully superheat the gas passing them. From the pipe G the gas passes down in the metal retort W, where it becomes well fixed, and then passes through the throat portion and pipe u into the condenser or scrubber, whichever preferred, and from there to the exhauster, by which the same is expedited to the purifiers and holder.

The apparatus is furnished with pressure-gages and test-lights, as usual.

Operation: Either when a new fire is started or the fire requires blowing up in the cupola, the gate o is closed, the oil-cocks f closed, and the seal-door h is opened. With steam from the pipe N' the gas, if any, in the cupola is readily expelled. The blower D is set in operation, and its valve connecting the blast with the cupola is opened. While the fire is being blown up, the water-pan L' is supplied by the pipe M. The hopper B is also supplied and its doors are closed. After the coal-bed in the cupola is properly lighted and the larger part has become properly heated the blower and its valve are stopped and closed. A charge of coal from the hopper is admitted, the seal-door h is closed, the valve o is opened, and the cocks f f are a little opened, the fire in the superheater W is properly in operation, and the water is flowing in the scrubber, the exhauster I is set in motion, and all its valves, with the by-pass, are opened. The oil-cocks f are now opened more fully. By the pipe O a limited supply of air is admitted in the water of the pan L'. By the bulls'-eyes X the condition of the fire is observed. By the test-lights the supply of oil is regulated with proper observation. By means of the vacuum and pressure gages the speed of the exhauster is guided and sufficient vacuum is allowed in the cupola to sparingly supply the fire with air and keep it from dying fast. A little steam is also supplied in the chamber L, and said vacuum is also sufficient to draw off the gas as rapidly as generated. Said fire is kept alive; but as soon as the volatile property of the lower part of the coal-bed has been distilled and exhausted, which is readily perceived by the observation through the bulls'-eyes X, the door J' is opened, and by assistance with the rakers the spent coal is discharged into the chamber K and the door J' closed again. From the hopper, by alternate opening and closing the doors S S, fresh coal is supplied, and this operation continues until the fire requires blowing up for a considerable time.

The chamber K may be cleaned out during the generation of the gas, and also water, steam, and air in limited quantities may be furnished in the pan L' during generation. After the fire has too much deadened the air-cock is stopped, the steam-cock is more fully opened, the valve o is closed and the door h is opened, and by the steam the remaining gas is expelled, the oil-cocks having been previously stopped. The exhauster and its valves are also stopped simultaneously with the valve o, and the blower and air-valve to the

cupola are opened and set in motion, as before described.

The striking advantages in this process are that the generation of the gas is done under partial vacuum, and therefore very rapid; that a large amount of carbureted hydrogen is obtained from the coal-distillation, and therefore less oil required to carburet the hydrogen; that by the long periods of generation a great deal of gas now wasted with short periods is saved.

The object of the rakers is mainly to forward all refuse coal and loosen clinkers toward the discharge of the grate.

Having fully described our invention, what we desire to claim and secure by Letters Patent is—

1. In combination with a cupola gas-generator, the continuous fuel feeder or charger, the inclined grate, and a sealed discharge-chamber for spent fuel arranged and operating as described. 85

2. The combination, in a cupola for generating gas, of a sealed coal-feeder, a sealed discharge-chamber with a water-receptacle, and a fixing-chamber, an air-inlet pipe opening into such receptacle, and a fixing-chamber, substantially as herein described. 90

3. In combination with the cupola-generator, the sealed coal-feeder, the sealed discharge-chamber, the oil-vaporizing retorts arranged in the walls of the cupola, a fixing-chamber, and a separate superheater for the generated gas, substantially as herein described. 95

4. In a gas apparatus, the combination of the cupola-furnace having an air-inlet pipe and means for vaporizing oil with a superheater, W, and its retort W' and gas-exhaustor, substantially as and for the purpose herein set forth. 105

5. In a gas-generating cupola-furnace, the combination of the ash-pit, its water-receptacle, and an air-supply pipe opening into it, with the inclined grate, the rakers or spent-coal forwarders, the sealed inlets for coal, and sealed outlets for refuse coal and ashes, substantially as herein described. 110

6. In combination with a cupola gas-generator, the sealed continuous fuel feeder or charger, the inclined grate, the rakers secured below such grate, and a sealed discharge-chamber for refuse arranged at the lower end of such grate, for the purpose described. 120

7. In a gas-generating cupola, the inclined grate and rakers, a sealed outlet and a sealed refuse-chamber arranged at the lower end of the grate, in combination with a double-sealed fuel-supply hopper, a distilling-chamber, and oil-vaporizing retorts, substantially as herein set forth. 125

8. In a gas-generator, the combination of the inclined grate, the sealed fuel-supply hopper, and the sealed outlet, arranged as described, with the oil-vaporizing retorts, and a fixing-chamber provided with tile shelves arranged as described, for the purpose set forth. 130

9. The cupola gas-generator having horizontal openings in its side walls, in combination with the removable oil gas-generating retorts secured in such side-wall openings, for the purpose described.

In testimony that we claim the foregoing as our invention we have signed our names, in

presence of two witnesses, this 22d day of June, 1885.

ROBERT M. POTTER.
REINHOLD BOEKLEN.
